ABSTRACT: A backing pump 4 for volatile fuel is constructed as an axial flow helical impeller pump operating in a cylindrical housing, having a tapered coaxial inlet portion at one end for connection to a small-diameter inlet line and a volute outlet at the other end. The helical vane extends to near the minimum diameter housing part at the inlet so that the pumped liquid, as it is accelerated through the length of the housing, will be substantially confined to an external part of progressively increasing inside diameter leaving a central "fluid hub" portion separated from it by a boundary zone and having little axial movement due to centrifugal action, vapors and gases will collect in the fluid hub, thus ensuring a substantially bubble-free outlet.

BACKING PUMPS MORE PARTICULARLY FOR VOLATILE LIQUIDS

In pumping systems for volatile liquids, and more particularly in aircraft fuel supply systems in which the liquid is to be delivered under high pressure by a volumetric pump, it is common to arrange at the inlet side of this pump a so-called backing pump in order to maintain an adequate inlet pressure for the volumetric pump, and it is usual to provide such a backing pump even in cases in which a transfer pump is arranged in the fuel tank or other point of liquid supply. Such backing pumps have hitherto been constructed as centrifugal pumps, which offer a high flexibility of output, but conditions may arise with volatile liquids, for example in the case of inoperativeness of a transfer pump or exhaustion of the supply of one of the transfer pumps, in which the liquid reaching the backing pump is liable to contain a high volumetric percentage of free vapor or gas (air) which, in the case of a centrifugal pump, may lead to depriming of the centrifugal pump and a consequent breakdown in pumping.

The present invention has for an object to provide an improved pump suitable for use as a backing pump for liquid which is volatile or liable to contain gases and/or vapors. Another object is to provide an axial flow impeller pump in which the flow of liquid is substantially confined to an annulus adjacent the circumferential wall of the pumping chamber while leaving a comparatively inert central core which increases in diameter from the inlet to the outlet as, due to the action of the impeller blades, the velocity of liquid increases from the inlet end towards the outlet end. This will ensure an outlet relatively free from gas and vapor bubbles.

The diameter of the inlet portion of the pump housing is preferably flared from a small diameter at the inlet towards a cylindrical portion and the helical impellers blades preferably commence near the smallest diameter portion of the housing so as to act upon the liquid as soon as it enters the pump, thus avoiding the hydrodynamic losses normally connected with a diffusor.

A fuel system incorporating a backing pump according to the invention constitutes another aspect of the invention.

One embodiment of the invention will now be described in more detail with reference to the accompanying drawing, which is a diagrammatic representation of a fuel system including a backing pump which is shown in axial section.

Referring now to the drawing, the illustrated fuel system includes a fuel tank 1 equipped with a transfer pump 2 which ensures the transfer of fuel from the tank 1, for example a wing-tip tank of an aircraft to a fuel transfer line 3 which leads via a backing pump 4 to a fuel metering and pressurizing pump 5, the latter is associated with a fuel control system 6 for the supply of fuel to a point of consumption illustrated as a burner nozzle 7. Under certain conditions, which often occur in high-altitude flight, the fuel in line 3 reaching the backing pump 4 is liable to be near its boiling point and, as a result of this, fuel entering the backing pump 4 is liable to contain a high volumetric percentage of free vapor and of gases which had been dissolved in the fuel. The presence of such gaseous admixtures render the use of a centrifugal backing pump unreliable. The backing pump employed according to the present invention is an axial flow impeller pump which has a generally cylindrical housing 8 which is formed at its inlet end with a flared portion 9 to provide a small inlet diameter substantially equal to that of the adjoining end 10 of the fuel transfer line 3, while the outlet end of the housing 8 is formed as a volute 11 whose outlet duct portion 12 is connected to the inlet of a metering pump 5 by a line 13. Accommodated in the housing is an impeller rotor mounted on a shaft 14. This rotor has a substantially cylindrical hub portion 15. From a point near the inlet end of the flared housing portion 9 and throughout the cylindrical housing portion 8, and which is equipped with four helical vanes 16 which extend from the hub 15 into close proximity of the wall of the pumping chamber to form a four-start impeller. The rotor is arranged to be rotated in the direction of the arrow A so that its helical turns will axially impel liquid

75 towards the volute 11. During operation of the pump, any liquid entering the housing chamber through the inlet 10 will be progressively accelerated both in the axial and tangential directions as it passes through the length of the housing portions 9 and 8.

5 Since the volume of the liquid remains constant during its passage through the pump, it follows from the increase in its axial velocity that the cross section, taken at right angles to the rotor axis, of the moving flow of liquid between the circumferential wall of the housing portions 9, 8 and the rotor hub 15 10 will decrease on its way from the entrance portion 10 to the volute 11 of the pump housing, and since, due to the tangential acceleration, the liquid will also assume a swirling motion about the rotor axis, this flow will, due, to centrifugal action, be confined to the outermost parts of the cross section, of the housing chamber. The liquid in the remaining part of the pump housing, i.e. the part nearer the rotor axis although forming a continuous body of liquid with the liquid participating 15 in this flow, will be substantially inert inasmuch as it has no effective axial velocity but merely participates in the rotation of the rotor, thus constituting a kind of liquid hub, and it will be appreciated that, due to the centrifugal action, any particles of free gas or vapor in the flow of liquid which moves from the inlet to the volute, will be displaced from the outer zone in 20 which the liquid flows, causing the particles to move towards the axis of the rotor into this liquid hub through the large area of direct liquid contact of the latter with the flow of axially moving liquid. Therefore, if the pump is arranged for vertical 25 upward flow, as is preferred, these particles can rise within this liquid hub towards the volute of the pump, which they will reach between the axis of the volute and the zone which is entered by the flow of pumped liquid; from this part of the volute they are preferably conducted, as pointed out further below, 30 through apertures 18. It will be observed that the helical vanes 16 of the rotor, which extend into close proximity of the cylindrical portion 8 of the housing, extend well into the flared housing portion 9, where they increase in diameter in accordance with the cone angle, from a point close to the 35 minimum diameter entry portion 10 of the housing, thus ensuring that impeller action is already effective in the flared portion 9 of the housing. This will ensure that the liquid being pumped is accelerated throughout its way through the pump housing and avoids pressure losses which are liable to occur in 40 increasing diameter portions of fluid conduits where diffuser action is relied upon to convert kinetic energy into pressure.

45 The helical impeller action can be utilized to obtain an appreciable increase in fluid pressure from the inlet to the outlet of the pump, and this will be conducive for the vapor and gas liberated from the incoming liquid at the entry of the pump, where the liquid is at its lowest pressure, to become recondensed or redissolved as the pressure of the pumped liquid increases towards the outlet end of the pump. In view of the centrifugal forces acting, this recondensation will take place in the vicinity of the border zone 17 between the zone of pumped liquid and the fluid hub, so that any implosive action connected with recondensation will take place well away from the housing wall and the impeller hub, thereby largely avoiding 50 any so-called cavitation damage. Any unabsorbed residue of gaseous components which may reach the volute 11, can be readily withdrawn by a vent system 18 connected to the volute at a convenient point of the liquid hub zone between the axis of the pumping chamber and the border zone 17.

55 Various details of the construction described with reference to the drawing may be modified without exceeding the scope of the invention. Thus the number of helical vanes need not necessarily be four but may be varied according to other considerations.

60 70 What we claim is:

75 1. An axial flow impeller pump, comprising a housing provided with a housing chamber having a longitudinal axis and a wall surface in the form of a surface of revolution about this axis, and with an axially directed inlet at one end of the chamber and open at its other end to a volute which is approx-

imately coaxial with said chamber; an impeller rotor mounted in this housing for rotation about said axis, said rotor having helical blades operative to apply, during rotation of the rotor, axial acceleration as well as tangential acceleration to any liquid entering the housing chamber through said inlet, with the cross-sectional area of the bladed rotor permitting the ratio of the total cross section available in the housing chamber for axial flow, to the cross section required for the axial flow of the amount of liquid actually passing through the pumping chamber, to increase progressively from the inlet end of the housing towards the volute, so that centrifugal action will cause the formation, inside a peripheral zone of liquid flowing from the inlet to the volute, of an inner body of liquid having substantially no effective axial velocity, said inner body of liquid being continuous with the liquid in said zone and extending into the volute chamber between said zone and the axis of the pumping chamber from a point near the inlet.

2. A pump as claimed in claim 1 wherein the blades of the impeller are in the form of a plural-start helix.

3. A pump as claimed in claim 1, wherein the housing 20

chamber has a cylindrical main portion and an inlet portion which is coaxial with the said main portion and is flared to increase from a small diameter at the inlet end of the housing chamber to reach, at its junction with the main portion of the housing chamber, the diameter of the said main portion.

5. A pump as claimed in claim 3, wherein the helical blades extend axially substantially throughout the length of the housing chamber from a point closely adjacent to the inlet.

10 6. A pump as claimed in claim 1, wherein the pump housing is provided with bleed aperture communicating with the volute at a point radially inside the surface of revolution separating the flow of pumped liquid from the inner body of liquid having no effective axial velocity.

15 7. A fuel system, which comprises an axial flow pump as claimed in claim 1, a fuel tank, a transfer pump associated with said fuel tank for transferring fuel from said pump axial flow pump, and a pressurizing pump having an inlet connected to the volute of said axial flow pump.
